UNITED STATES PATENT OFFICE.

CYRUS NEWHALL, OF HINSDALE, NEW HAMPSHIRE.

IMPROVEMENT IN HARVESTERS.

Specification forming part of Letters Patent No. 36,017, dated July 29, 1862.

To all whom it may concern:

Be it known that I, CYRUS NEWHALL, of Hinsdale, in the county of Cheshire and State of New Hampshire, have invented a new and Improved Grain and Grass Harvester; and I do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a horizontal section of the same, taken in the line $y y$, Fig. 1.

Similar letters of reference indicate corresponding parts in the two figures.

To enable those skilled in the art to fully understand and construct my invention, I will proceed to describe it.

A represents the main frame of the machine, which I prefer to have constructed of metal in tubular form, as shown at $a a a a a$, in order to obtain strength and durability in connection with lightness; and B is the axle, which is permanently attached to the main frame A, and has a wheel, C, placed loosely on one end of it, and radial arms D attached permanently to its opposite end, the arms D being each provided with a roller, E, at its end, on which a rim, C', which constitutes the other wheel of the axle B, is placed. The rollers E are each grooved at their peripheries to receive a flange, a, at the inner side of rim C', which secures said rim to the rollers E.

The diameter of the rim C' is equal to that of the wheel C, and the rim is allowed to rotate freely on the rollers E, the arms D of which are fixed, in consequence of being attached permanently to the axle B, as previously stated.

To the main frame A there is attached by joints $b' b'$ a frame, F, which may be formed of two rods, $b b$, connected by a cross-bar, d. This frame F extends down between the two lower arms, D D, and projects a short distance beyond them. The lower end of this frame F has a shoe, G, attached to it by joints $e e$, and to this shoe a finger-bar, H, is connected, the joints $e e$ admitting of the finger-bar being elevated to a vertical position when the machine is being drawn from place to place, the finger-bar being retained in this position by a catch, e, on one of the upper arms, D, as shown in Fig. 1.

On the finger-bar H there is placed a sickle, I, which may be of the ordinary kind, or such

as are used with a reciprocating movement. This sickle I is connected by a rod, J, with a crank-pulley, K, on the back end of a shaft, L, on the main frame. This shaft L is rotated by means of bevel-gears $f g$ from a shaft, M, at the front part of the main frame A, said shaft being rotated by pinions $h h$, which gear into teeth i at the inner side of the wheel C and rim C'. The pinions $h h$ are placed on independent shafts $M' M'$, which are in line with the shaft L, and are connected with it by clutches N N, said clutches being operated by levers O O, rods P P, and a hand-lever, Q, as shown in Fig. 2.

The finger-bar and sickle may be elevated to pass over obstructions, when necessary, by means of a lever, R, and chain S, the latter being attached to frame F and to the back end of lever R, which is hung loosely on the axle B, and has its front end passing through a perforated segment-guide, T, in which a pin, j, is fitted to retain the lever R at any desired point.

In consequence of having the wheel C' arranged as shown and described, the finger-bar H may be placed in line with the axle B, as shown in Fig. 2, and a direct sickle-driving mechanism obtained. The sickle, therefore, it will be seen, will rise and fall simultaneously with the wheels C C', and be allowed to conform perfectly with the irregularities of the surface of the ground over which it passes, thereby insuring a cut of uniform height, while the draft of the machine, owing to the simple and direct sickle-driving mechanism, is rendered quite light and easy for the team.

I am aware that the finger-bars of harvesters have been previously placed in line with the axle of the machine; but such an arrangement, so far as I am aware, has hitherto involved the necessity of comparatively complicated sickle-driving mechanism, in order to avoid the "off" wheel of the machine—a contingency which is fully obviated by my invention.

Having thus described my invention, what I claim as new, and desire to secure by Letters Patent, is—

The arrangement of the frame F, constructed as shown, with the rim C', shoe G, and the main frame A, in the manner herein shown and described.

CYRUS NEWHALL.
